US00D945626S

(12) **United States Design Patent** (10) **Patent No.:** **US D945,626 S**
(45) **Date of Patent:** **** Mar. 8, 2022**

(54) **MEDICATION DELIVERY CARTRIDGE**

(71) Applicant: **AceAge Inc.**, Burlington (CA)

(72) Inventors: **Donald Spencer Waugh**, Hamilton (CA); **Wesley van Ooyen**, Burlington (CA); **Dylan Horvath**, Toronto (CA); **Borys Chylinski**, Toronto (CA)

(73) Assignee: **AceAge Inc.**, Burlington (CA)

(**) Term: **15 Years**

(21) Appl. No.: **29/717,593**

(22) Filed: **Dec. 18, 2019**

(51) LOC (13) Cl. **24-02**

(52) U.S. Cl.

USPC **D24/185**

(57) **CLAIM**

The ornamental design for a medication delivery cartridge, as shown and described.

DESCRIPTION

FIG. 1 illustrates a perspective view of a medication delivery cartridge showing our new design.

FIG. 2 illustrates a right side elevation view thereof.

FIG. 3 illustrates a left side elevation view thereof.

FIG. 4 illustrates a front elevation view thereof.

FIG. 5 illustrates a rear elevation view thereof; and,

FIG. 6 illustrates a top plan view thereof.

The broken lines illustrating portions of the medication delivery cartridge form no part of the claimed design.

1 Claim, 6 Drawing Sheets
